C. S. BUCKLIN.
HAND PACK FILLING MACHINE.
APPLICATION FILED APR. 22, 1920.

Patented Oct. 31, 1922.

2 SHEETS—SHEET 2.

Inventor:
Charles S. Bucklin,
Atty.

UNITED STATES PATENT OFFICE.

CHARLES S. BUCKLIN, OF REDBANK, NEW JERSEY, ASSIGNOR TO SPRAGUE CANNING MACHINERY COMPANY, OF CHICAGO, ILLINOIS, A CORPORATION OF ILLINOIS.

HAND-PACK-FILLING MACHINE.

Application filed April 22, 1920. Serial No. 375,848.

To all whom it may concern:

Be it known that I, CHARLES S. BUCKLIN, a citizen of the United States, residing at Redbank, in the county of Monmouth and State of New Jersey, have invented new and useful Improvements in Hand-Pack-Filling Machines, of which the following is a full, clear, concise, and exact description, reference being had to the accompanying drawing, forming a part of this specification.

This invention relates to improvements in canning machines, and more particularly to hand packed fillers.

One object of this invention is to provide an improved hand pack filler in which a plurality of movable supports is operated by a single driving means, thereby resulting in an increased supply of fruit for maximum filling operations.

Another object is to provide a unitary gravity can feed to supply cans to the operators for all the movable supports.

Another object is to provide a unitary means for removing the filled cans from the operators for all the movable supports.

Another object is to provide an improved filler of the hand pack type which will facilitate the packing of whole vegetables and fruit, this being especially desirable when tomatoes are packed.

Other objects will appear from the detailed description and appended claims.

Fig. 1 is an end view of the hand pack filler;

Fig. 2 is a plan view of the hand pack filler taken on the line 2—2 of Fig. 1;

Fig. 3 is a vertical sectional view of the invention taken on the line 3—3 of Fig. 1 looking in the direction of the arrows; and

Fig. 4 is a vertical sectional view of the invention taken on the line 4—4 of Fig. 1 looking in the direction of the arrows.

In order to give a general idea of the invention, it is here stated that the construction shown comprises a supporting frame 10 resting at one end on the floor or any suitable support therefor, and at the other end on a platform 11 upon which the operators stand while filling the cans. Suitably supported by the frame 10 is a plurality of endless belts or movable supports 12 which are driven by a single roller 13 from their lower ends, this roller being, in turn, driven

by a pulley 14 from any suitable source of power.

Another roller 15 carries the endless belts 12 at their upper ends, the roller 15 being disposed in a relatively higher plane than the roller 13, the belts 12, therefore, sloping upward. The belts travel in a clockwise direction and carry the fruit up to the high end thereof.

Disposed above the endless belts 12 in the same sloping plane are boxes 16 in which the vegetables or fruit are received. These boxes 16 are open at the bottom and at their upper ends so that the article received by the boxes will travel on the belts to the upper end of the boxes and will be within reach of the operator when standing on the platform 11 at the rear of the machine.

A drain board 16^a is disposed below the boxes 16 and belts 12, said board emptying into a V-shaped sloping trough 17. These two draining members 16^a and 17 extend the width of the machine to catch any water or juice from the boxes 16.

To give a more detailed description of this construction, the support 10 comprises two pair of vertically disposed members 20 and 21 which are braced near their lower ends by the members 22 and 23 formed integral therewith.

Bolted to the front supports 20 near the outer ends thereof are brackets 24, the inner ends thereof being formed into bearings 25, which bearings support the shaft 26 upon which the long roller 13 is mounted, said roller extending the width of the machine and being rotatably mounted by means of the shaft 26 in the bearings 25 in brackets 24. The drive pulley 14 is secured to the shaft 26 upon which pulley a belt 27 is engaged to drive the endless belts 12 (Fig. 1).

The rear supports 21 are suitably mounted upon the standing platform 11 and have bolted thereto near their upper ends brackets 28, which extend inwardly, each bracket having a bearing 29 formed therein in which bearings is rotatably mounted a shaft 30 having the roller 15 rotatable therewith and upon which the endless belts 12 travel.

The endless belts 12 are shown herein five in number and equally distanced along the roller 13. A greater or less number of belts

could be shown without departing from the invention herein, this being governed by the size of machine desired. Each of these belts 12 is disposed in the same sloping plane and are driven in a clockwise direction by the pulley 14 from any suitable source of power through the belt 27.

The brackets 24 and 28 have formed integral therewith upwardly projecting supporting arms 32 and 33 respectively which extend at right angles to the sloping plane of the endless belts 12. Between these arms 32 and 33 and bolted thereto is the plurality of boxes 16, these boxes being disposed in the same sloping plane as the endless belts 12.

Disposed below the boxes 16 in substantially the same plane as the endless belts 12 is the drain board 16^a which empties into the V-shaped trough 17. This board 16^a is held in inclined position in any suitable manner. The juice, water, etc., which may drip from the belts 12 will flow down the board 16 and into the trough 17, said trough being sloped downwardly from one end of the machine to the other, being supported at one end by the upper brace rod 22 and at the lower end by the lower brace rod 23, the trough being cut away at its lower end, as shown at 35, to pass between the brace members 22 and 23 to empty the contents therein clear of the machine.

In order to increase the speed with which the cans may be filled by hand packing, it is necessary that the empty cans be in a position easily accessible to the operator; also, that the can rest upon which the cans are placed when filled be in a most advantageous position, and that the means for transferring the cans to the next machine after they are filled be in a position within easy reach of the operator. In other words, it is desired that these three positions from which the cans are transferred during the filling operation be within close proximity of each other.

To accomplish this result, a can feed is provided which is supported by a rod 36 extending transversely across the upper edge of the boxes 15 at the open ends thereof. A substantially Y-shaped bracket member 37 is bolted to the rod 36 at each end of the machine, which brackets have secured thereto long flat side rods 38 and a long flat base rod 38^a extending from one end of the machine to the other, as shown in Fig. 3.

These rods extend vertically at 39 to form a gravity chute for the cans. The cans may be removed from the can feed at any point thereof by the operator as desired, the weight of the cans in the vertical portion of the chute keeping the cans moving to replace those removed by the operator.

The can rest 40 on which the operators

place the cans for filling extends the width of the machine and is supported on and bolted to the brackets 28 at the rear of the machine. Formed integral with the can rest 40 is a flange portion 41 which is extended substantially at a right angle to the sloping plane in which the boxes 16 and belts 12 are disposed. This flange portion 41 extends upwardly to a position slightly above the plane of the upper surface of the endless belts 12, and being so positioned forms a barrier against which the fruit is urged by the movable supports or belts 12. This barrier will prevent the vegetables or fruit from falling from the boxes and serves also to cause the fruit to pile up at the upper end of the box to keep the operator well supplied at all times.

After the cans have been filled, they are removed from the can rest 40 and placed on a horizontal conveyor 42 which travels in an anti-clockwise direction from one end of the machine and carries the filled cans to the place of the next operation. This conveyor comprises a stationary guiding rack 42 for guiding the cans on a chain conveyor 44 which extends through the rack and travels along the bottom thereof. The conveyor is mounted to travel over a roller 45 which is mounted on the support 21, as shown in Fig. 1. This roller 45 is driven by suitable means through a pulley 46 (Fig. 3).

The operation of the device is as follows: The vegetables or fruit used which, for this purpose of description, may be tomatoes, are emptied into the boxes 16 which are positioned to be within convenient reach of the person filling the boxes. These boxes are open at the bottom thereof and the tomatoes emptied thereinto will engage the endless belts or movable supports 12 which supports form the bottoms for the boxes. The machine is set in motion, being driven from the belt 27 which drives the endless belts 12 in a clockwise direction and conveys the tomatoes along the belts to the upper open end of the box. The tomatoes are, however, prevented from falling off the ends of the belts by the barrier 41 which also causes the tomatoes to pile up at the upper end of the boxes to keep the operator well supplied. This barrier is formed integral with the can rest 40 upon which the cans are placed when being filled.

Within convenient reach of the operator is the can feed which will be supplied with empty cans at all times from the gravity can chute 39, the cans in said chute forcing the empty cans along the can feed and keeping the same well supplied. The cans may be removed from the can feed by the operators at any place thereon. The operator removes the cans from the can feed, then places them on the can rest 40 where they are filled by

the operator and then placed on the conveyor 42 which carries the cans to a suitable place for the next operation.

It is particularly noted that the three operations necessary in filling the cans, namely, removing the empty cans, filling same, and placing the filled cans on the conveyor may be accomplished by the operators, without stooping or extended reaching on their part, thereby lessening the danger of injury to the operators and also increasing the speed at which the cans may be filled.

My Patent No. 1,335,819, dated April 6, 1920, contains generic claims covering the construction shown in this application.

Having thus described my invention, what I claim as new and desire to secure by Letters Patent is:

1. In a device of the class described, a plurality of fruit receptacles, a movable support for each receptacle on which the fruit rests, and a combination can rest and barrier extending along one end of all of said movable supports.
2. In a device of the class described, a plurality of fruit receptacles, a movable support for each receptacle on which the fruit rests, a plurality of means extending along one end of all of said movable supports for supplying the cans to the operator at each movable support, and for receiving the cans from the operator at each movable support, said means comprising a can feed and a can conveyor, and a can rest positioned substantially midway between said can feed and conveyor, and a can rest also extending along one end of all of said movable supports.
3. In a device of the class described, a plurality of fruit receptacles, a movable support for each receptacle on which the fruit rests, a plurality of means extending along

one end of all of said movable supports for supplying the cans to the operator at each movable support, and for receiving the cans from the operator at each movable support, 45 said means comprising a can feed and a can conveyor, and a can rest positioned substantially midway between said can feed and conveyor, said can rest also extending along one end of all of said movable supports, and 50 having a flange thereon forming a barrier which also extends along one end of all of said movable supports and against which said supports urge the fruit.

4. A hand pack filling machine comprising endless belt means on which the fruit rests, of sufficient extent to supply the fruit for a plurality of operators, and a combined can rest and barrier extending across said endless belt means, and serving as a barrier 55 against which said fruit is urged by said endless belt means and as a support for the cans to be filled.

5. A hand pack filling machine comprising endless belt means on which the fruit 65 rests, of sufficient extent to supply the fruit for a plurality of operators to handle, barrier means extending across said endless belt means against which said endless belt urges the fruit, can rest means also extending 70 across said endless belt means on which the cans are placed for filling, means above said can rest means for supplying empty cans for all of the operators, and means underneath said can rest means for removing filled cans 75 placed thereon by the operators.

In witness whereof, I have hereunto subscribed my name.

CHARLES S. BUCKLIN.
